UNITED STATES PATENT OFFICE.

JESSE M. PAYNE, OF LEE COUNTY, AND GEORGE G. WALLACE, OF RUSSELL COUNTY, ALABAMA, ASSIGNORS TO PERFECTION DYEING MACHINE COMPANY, OF COLUMBUS, GEORGIA, A CORPORATION OF GEORGIA.

DYEING APPARATUS.

1,053,063.

Specification of Letters Patent. Patented Feb. 11, 1913.

Application filed April 10, 1912. Serial No. 689,811.

To all whom it may concern:

Be it known that we, JESSE M. PAYNE and GEORGE G. WALLACE, citizens of the United States, residing, respectively, in the county 5 of Lee and in the county of Russell and State of Alabama, have invented certain new and useful Improvements in Dyeing Apparatus; and we do hereby declare the following to be a full, clear, and exact description of the invention, such as will enable others skilled in the art to which it 10 pertains to make and use the same.

Our present invention relates to improvements in apparatus for dyeing and drying 15 yarns of cotton, or other textile material, and relates more especially to an improved construction of hollow warper beam, on which the yarn is wound, and upon which said yarn is dyed, washed, and dried, without necessitating the removal thereof from 20 said warper beam.

The invention is especially intended to provide a hollow warper beam having a series of slats, forming the slotted cylindrical 25 portion upon which the yarn is wound, with means for reciprocating adjacent slats outwardly and inwardly in reverse directions, whereby during the treatment of the yarn while on the beam, the dye liquor and washing fluid have free access to the yarn immediately contiguous to the slats, and whereby 30 any streaky effect, due to continuous contact of the yarn with the slats, incident to the dyeing, washing, or other treatment of the 35 yarn, is avoided.

Our invention is especially intended to provide improvements in the apparatus illustrated and described in our Patent No. 887,511, granted May 12, 1908, for "Improvements in dyeing machines," and in our 40 application, Serial No. 609,794, filed February 20, 1911, and also entitled "Improvements in dyeing machines."

Our invention will be understood by reference to the accompanying drawings, in which the same parts are indicated by the same letters and numerals throughout the several views.

Figure 1 is a central longitudinal section 50 through the improved warper beam, parts being shown in elevation, and parts being broken away. Fig. 2 shows a cross-section along the line 2-2 of Fig. 1, and looking

in the direction of the arrows. Fig. 3 is a detail showing one of the slats detached from the apparatus. Fig. 4 shows a section through the inclosing vat and closed tank, in which the warper beam is mounted, and shows modified means for actuating the slats. Fig. 5 is a similar view to Fig. 4, but on a larger scale, and shows another modification, in which the slats may be actuated while the warper beam is in the closed tank, and while it is being rotated. Figs. 6 and 7 are details, showing the means for coupling together the interrupted sleeve and shaft of Fig. 5.

This invention relating more particularly to the warper beam and the method of expanding and contracting the slats, only such details of the apparatus are shown as are necessary to explain this operation; but the complete details of the apparatus are shown in our application, Serial No. 609,794, afore- 75 said.

Referring to Fig. 4 of the drawings herein, the outer wooden vat A incloses the inner closed tank or jacket B, having the cover C and the head B', which head, and the head A' of the vat A, are perforated to receive 80 the pipe D, as fully described in our application aforesaid.

Referring now especially to Figs. 1, 2, and 3, E represents the warper beam, mounted upon the shaft 1, having the projecting ends 85 1^a, to one of which ends is connected a drive shaft G, shown to the right of the figure, which carries the worm wheel 2, engaging the worm 3, driven by the pulley 4. Any suitable driving mechanism for rotating the 90 shaft 1 may be adopted, and we do not mean to confine ourselves to the specific means indicated.

The warper beam is hollow, and in the form of a spool, and it is provided at one 95 end with a head 5, having perforations therethrough, as at 6, and notches, as at 7, between the shoulders 8 and 9, to receive the ends of the slats 10. The opposite head 5^a is provided with similar slots 7^a, and with 100 shoulders 8^a and 9^a, to receive the opposite ends of said slats. These slats are notched at each end, as at 11, (see Fig. 3) to permit radial play in the slots 7 and 7^a; and on their inner faces, said slats are provided 105 with a series of wedge plates 12 and 12^a, se-

cured thereto in any convenient way, as indicated in Fig. 3. The wedge plates 12 on one slat are reversely disposed to the corresponding wedge plates 12^a on the adjacent slat, as shown most clearly in Fig. 1; and these wedge plates on adjacent slats alternately engage the inner wall of the radial slots 13 in the rims 14 of the spiders 15, which spiders are slidably mounted on the shaft 1, and are connected together by rods 16, but are spaced apart by spacing sleeves 17, so that these various spiders, together with the rods and sleeves, constitute a sliding frame, which is adapted to travel 15 through a slight distance longitudinally in reverse directions upon the shaft 1. The reciprocal movement of this frame, when carried to the limit of travel in one direction, presses the wedge plates 12 outwardly, 20 as shown in Fig. 1, and causes the corresponding slats to be forced outward, while the adjacent wedge plates 12^a are then clear of the bottom of the slots 13, and the slats carrying said plates 12^a are free to move 25 inwardly a slight distance toward the shaft 1. This reciprocal movement of the spider frame for actuating the wedge plates 12 and 12^a, may be effected in a variety of ways, one of which I have shown in Figs. 1 and 2, 30 and others in Figs. 4 and 5.

Referring first to Figs. 1 and 2, one of the spiders 15^a is provided with fixed nuts 18 and 18^a, adapted to engage the screws 19 and 19^a, respectively, which screws carry 35 sprocket chains 20, engaging the sprocket wheel 21; and one of said screws, as 19^a, is turned by means of a squared end and hand crank 19^b, or other suitable device, not shown. The sprocket chain 21 transmits 40 movement from the screw 19^a to the other screw 19. These screws 19 and 19^a are revolvably mounted, but held against longitudinal movement in journal bearings 22, carried by the head 5^a. By having two 45 screws and nuts equal distances away from, and on opposite sides of, the shaft 1, there will be no tendency to bind, as would be the case if a single screw only were used.

In the form of device shown in Fig. 4, 50 the spider 15^b, nearest the head 5^a, is provided with a sleeve 23, having a coarse screw-thread 24, engaging the corresponding screw-thread 25 on the interior of the sleeve 26, carrying the wheel 27, which is 55 mounted inside of the thrust collar 28, carried by the end 1^a of the shaft 1. By turning this wheel 27 by hand, the spider frame may be moved in either direction; but, if preferred to operate this wheel 27 by means 60 of the motive power geared on to the shaft 1, as shown to the right of Fig. 1, it will be sufficient to provide any suitable brake for said wheel, such, for instance, as a band brake, well known in the art, and which is 65 not illustrated in the drawings. By apply-

ing this brake when the shaft 1 is being driven in one direction, the spider frame would be moved in the direction of the arrows 4; while by reversing the motion of the shaft 1, and applying the band brake, 70 the spider frame may be moved in the reverse direction.

It will be noted that, in the apparatus shown in Figs. 1, 2, and 4, it will be necessary to remove the cover from the closed 75 tank B, if the warper beam is used in a closed tank; but in Figs. 5 to 7, we have shown an arrangement by means of which the slats may be expanded or contracted, irrespective of whether the tank inclosing 80 the warper beam is closed or open, and in which this may be effected either by hand or by the motive power applied to rotating the shaft 1. Referring to these Figs. 5 to 7, the end spider 15^c is provided with a 85 sleeve 30, projecting through the head 5^a of the warper beam, which sleeve is preferably provided with the slot 31, to engage the spline 32, projecting from the hub of the head 5^a into said slot, so that the sleeve 90 may be free to slide, but may be held against rotation relative to the head 5^a and the shaft 1. This sleeve 30 is provided with a flange 33, adapted to couple onto a similar flange 33^a, carried by the sleeve 30^a, which 95 sleeve 30^a is provided with coarse screw-threads 34, to engage corresponding screw-threads in the sleeve 35, carrying the hand wheel 36. This sleeve 30^a passes through the head B' of the closed tank B, shown 100 more in detail in Fig. 4; and mounted in this sleeve is the rod 37, which forms a continuation of the shaft 1, and is connected thereto in any convenient way, as by means of the T-head 39 and the T-groove 39^a, 105 shown in detail in Figs. 6 and 7. The outer end of this rod 37 carries a set collar 38, which is preferably provided with antifriction end thrust bearings 38^a. The flanges 33 and 33^a of the sleeves 30 and 30^a may be 110 connected together in any convenient way, as by means of the hinged bolts 40, engaging in the notches 42 of said flanges, and the butterfly nuts 41. To secure a firm joint, one 115 of the flanges, as 33, may be provided with a boss 43, to project into the corresponding recess 44 in the opposite flange. We do not mean to limit ourselves, however, to an 120 special mode of connecting the sleeves 30 and 30^a, or the shaft 1 and rod 37 together, 125 as this may be done in a great variety of ways.

In the position shown in Fig. 5, the spider frame is at one end of its travel, and is pressing the wedge plates 12 outwardly, while the 125 wedge plates 12^a are in their innermost position. By turning the hand wheel 36 in the proper direction to move the spider frame in the direction of the arrows 5, the wedge plates 12 will be disengaged, and the wedge 130

plates 12^a will be forced outward. This reverse direction may be given to the spider frame either by operating the hand wheel 36 by hand; or, if preferred to use the power already engaged in rotating the shaft 1, by simply holding the hand wheel 36, or by applying a brake thereto, the rotation of the shaft 1 would itself cause the sleeve 30^a to rotate inside of the sleeve 35, and the screw-threads 34 would move the spider frame in one direction. To move the spider frame in the other direction, it will only be necessary to reverse the direction of motion of the shaft 1, still holding onto the hand wheel 36, or applying a suitable brake thereto.

In any of the forms of apparatus hereinbefore described, it will be noted that the movement of the spider frame in one direction will force out the alternate slats of the warper beam, and will permit the adjacent slats to move in toward the center of the warper beam, which motion will be positively effected, not only by the force of gravity acting upon the slats in the upper section of the warper beam, but also by the tension of the layers of yarn wound thereon, so that as soon as these slats are free to move inward toward the shaft 1, they will so move, permitting free access of the dyeing, washing, or other fluid, to those parts of the yarn which had lately been more or less inaccessible to such fluid, owing to the contact of said yarn with said slats. This shifting of the alternate groups of slats inward or outward may be effected as often as may be found desirable in practice.

It will be obvious that, in the form of device shown in Fig. 5, the screw-threads 34 and hand wheel 36 will be outside of the closed tank or jacket B, and may be conveniently operated without opening said tank, or stopping the mechanism for driving the shaft 1.

In order to remove the warper beam shown in Fig. 1 from the tank, hooks or slings may be used to engage the ends 1^a of the shaft 1. In a similar way, the warper beam shown in Fig. 4 may be removed from the tank B; but to remove the warper beam shown in Fig. 5 from said tank, it will be necessary first to remove the cover of the tank, then disengage the bolts 40 and butterfly nuts 41, and slide the sleeve 30^a back clear of the joint 39, which may be done by rotating the hand wheel 36, and then uncoupling the rod 37 from the end of the shaft 1.

For convenience in mounting the end of the warper beam in the tank B, any suitable support may be provided for the end of the warper beam next the closed head 5^a, such as the support F, shown diagrammatically in Fig. 5.

We do not mean to limit ourselves to any specific details of construction, or any spe-

cific arrangements for operating the herein described apparatus, except such as will be hereinafter set forth in the claims.

Having thus described our invention, what we claim and desire to secure by Letters Patent of the United States is:—

1. The combination in a hollow warper beam of a plurality of slats forming the periphery of said warper beam, and mounted to move radially away from the axis thereof, and means for reciprocating alternately adjacent slats outwardly and inwardly away from or toward the axis of said warper beam, substantially as described. 75

2. The combination in a hollow warper beam of a plurality of slats forming the periphery of said warper beam, and mounted to move radially away from the axis thereof, and means for simultaneously moving the alternate slats in groups away from or 80 toward the axis of said warper beam, substantially as described. 85

3. The combination in a hollow warper beam of a plurality of slats forming the periphery of said warper beam, and mounted to move radially away from the axis thereof, and means for moving a series of alternate slats in groups away from or toward the axis of said warper beam, said means comprising a series of reversely disposed 90 wedge plates secured on the inside of said slats, and a longitudinally movable frame mounted interior to said slats and adapted to engage said wedge plates, with means for moving said frame longitudinally, substantially as described. 95

4. The combination in a hollow warper beam of a plurality of slats forming the periphery of said warper beam, and mounted to move radially away from the axis thereof, and means for simultaneously moving the alternate slats in two separate groups away from or toward the axis of said warper beam, said means comprising a series of reversely disposed wedge plates secured on the 105 inside of said slats, and a longitudinally movable frame mounted interior to said slats and having bearing faces adapted to engage said wedge plates, with means for moving said frame longitudinally, substantially as described. 110

5. The combination in a hollow warper beam of a central shaft, and a pair of heads mounted thereon, and provided with recesses in the inner sides thereof, a plurality of 120 slats forming the periphery of said warper beam, and mounted to move radially away from the axis thereof, said slats having their ends loosely fitting in said recesses in the heads, and means for moving a series of alternate slats in groups away from or toward the axis of said warper beam, substantially as described. 125

6. The combination in a hollow warper beam of a central shaft, and a pair of heads 130

mounted thereon, and provided with recesses in the inner sides thereof, a plurality of slats forming the periphery of said warper beam, and mounted to move radially away from the axis thereof, said slats having their ends loosely fitting in said recesses in the heads, and means for simultaneously moving the alternate slats in groups away from or toward the axis of said warper beam, substantially as described.

7. The combination in a hollow warper beam of a central shaft, and a pair of heads mounted thereon and provided with recesses in the inner sides thereof, a plurality of slats forming the periphery of said warper beam, and mounted to move radially away from the axis thereof, said slats having their ends loosely fitting in said recesses in the heads, and means for moving alternate slats in groups away from or toward the axis of said warper beam, said means comprising a series of reversely disposed wedge plates secured on the inside of said slats, and a longitudinally movable frame mounted interior to said slats and adapted to engage said wedge plates, with means for moving said frame longitudinally on said shaft, substantially as described.

8. The combination in a hollow warper beam of a central shaft, and a pair of heads mounted thereon, and provided with recesses in the inner sides thereof, a plurality of slats forming the periphery of said warper beam, and mounted to move radially away from the axis thereof, said slats having their ends loosely fitting in said recesses in the heads,

and means for simultaneously moving the alternate slats in two groups away from or toward the axis of said warper beam, said means comprising a series of reversely disposed wedge plates secured on the inside of said slats, and a longitudinally movable frame mounted interior to said slats and adapted to engage said wedge plates, with means for moving said frame longitudinally, substantially as described.

9. In a revolving collapsible dyeing beam suitably mounted series of yarn supporting slats, and means whereby one series of said slats are adapted to be collapsed independently of and at a different time from the other series.

10. In a revolving collapsible dyeing beam, a supporting shaft, heads fixed thereon, a plurality of slat expanding rings slidably mounted on said shaft, a series of radially movable slats supported and expanded by said rings when moved in one direction, said slats being permitted to retract when said rings are moved in the opposite direction, and means on said slats whereby one series thereof is expanded and permitted to retract independently of and at a different time from the other series.

In testimony whereof, we affix our signatures, in presence of two witnesses.

JESSE M. PAYNE,
GEORGE G. WALLACE.
